US00D602043S

(12) **United States Design Patent**
Linnig

(10) **Patent No.:** **US D602,043 S**
(45) **Date of Patent:** **** Oct. 13, 2009**

(54) **HUB FOR AN ELECTROMAGNETIC COUPLING FOR MOTOR VEHICLES**

(75) Inventor: **Karl Heinz Linnig**, Markdorf (DE)

(73) Assignee: **Kendrion Linnig GmbH** (DE)

(**) Term: **14 Years**

(21) Appl. No.: **29/246,169**

(22) Filed: **Mar. 3, 2006**

(30) **Foreign Application Priority Data**

Sep. 6, 2005 (DE) 405 04 629

(57) **CLAIM**

The ornamental design of a hub for an electromagnetic coupling for motor vehicles, as shown.

DESCRIPTION

FIG. 1 is a top view of a hub for an electromagnetic coupling for motor vehicles.

FIG. 2 is an enlarged top view of the hub illustrated in FIG. 1; and,

FIG. 3 is a perspective view of the first embodiment illustrated in FIG. 1.

The broken lines in the drawings show the environment of the invention and form no part of the claimed design.
